UNITED STATES PATENT OFFICE.

EDWIN M. GOLDSMITH, OF PHILADELPHIA, PENNSYLVANIA.

COMBINED BRAID-HOLDER AND BODKIN-CARRIER.

1,054,763.

Specification of Letters Patent.

Patented Mar. 4, 1913.

Application filed September 13, 1912. Serial No. 720,155.

To all whom it may concern:

Be it known that I, EDWIN M. GOLDSMITH, a citizen of the United States, residing at Philadelphia, county of Philadelphia, and 5 State of Pennsylvania, have invented a new and useful Improvement in Combined Braid-Holders and Bodkin-Carriers, of which the following is a full, clear, and exact description, reference being had to the 10 accompanying drawings, which form a part of this specification.

The object of my invention is to produce a combined holder for braid, tape, ribbon, cord, etc., and carrier for a bodkin so arranged as to present the following advantage of retention of the bodkin in such position that it may be readily removed and replaced, as well as the advantage of application 15 of the bodkin to the carrier in such position and in such relation to the braid that the braid will, upon removal of the bodkin, be automatically threaded thereto.

The invention is applicable to holders that are also receptacles, as well as to holders in 25 the form of spools, reels, cards, etc. Where the invention is applied to receptacles, the latter is preferably so constructed and the bodkin so applied that such part of the tape as projects outside the receptacle will be 30 concealed except a short length thereof that it is desirable to expose in order that the buyer or user may, without disturbance of the box, be apprised of the quality and color of the braid.

35 To attain these objects I have devised the several embodiments of my invention set forth in the accompanying drawings and the following description and have pointed out in the claims the essential features thereof.

40 In the drawings: Figure 1 is a perspective view of one form of application of the invention to a box; Fig. 2 is a side elevation, partly in section of Fig. 1; Fig. 3 is a view, similar to Fig. 1, showing a modified construction of box; Fig. 4 is a view, similar to Fig. 2 of the modification of Fig. 3; Fig. 45 5 is a plan view of an embodiment of my invention in a card; Fig. 6 is a plan view of an embodiment of my invention in a reel or spool.

The body *a* of the boxes of Figs. 1, 2, 3 and 4, may be constructed in any convenient way, it being desirable to make it nearly or quite square so as to contain a reel of braid *b*, which, when of full size, will substantially fill the box.

In one of the narrow sides of the box I provide the three slots, *c* *d* and *e*, and in front of the slot *e* I provide a projection *f* (Figs. 1 and 2) or *g* (Figs. 3 and 4). The 60 projection *f* extends cross-wise and is of slightly less length than the transverse eye *m* with one or more of which a bodkin, as *k*, is usually provided. The projection *g* extends lengthwise of the box and is of 65 slightly less length than the longitudinal eye *n* with which a bodkin is usually provided.

In front of the projection *f* or *g* are the ears *h* and *i*. Each ear extends up from one 70 edge of the side of the box and is thence bent toward the other edge. These ears are located along opposite edges, one in advance of the other.

The braid is pulled through the slot *c*, 75 thence extends along the exposed face of the box to and through the slot *d*, thence extends along the interior face of the box to and through the slot *e* and thence extends a short distance along the exposed face of 80 the box, being pulled over the projection *f* or *g*.

The bodkin *k* may be applied to the box either by slipping the bodkin, in the direction of its length, beneath the ears *h* and *i* 85 and then forcing the transverse eye *m* or the longitudinal eye *n* into engagement with the projection *f* or *g*, the braid being passed over the projection before engagement by the bodkin; or the projection *f* or *g*, with 90 the braid drawn over it, may first be forced through the eye *m* or eye *n*, and the rear of the bodkin then successively slipped under the ears *h* and *i*, there being usually sufficient resiliency in the bodkin and holder 95 to make this mode of engagement possible.

The bodkin is thus held securely in place on the box and a small section of the braid *b* is exposed to view between the slots *d* and *e*. When the bodkin is removed, the end 100 of the braid is removed with it, having been automatically threaded thereto in the application of the bodkin to the box. It is only necessary for the user to pull on the loop projecting through the eye *m* or *n* of the 105 bodkin, and the extremity of the braid is thus pulled through such eye, as shown in dotted lines Fig. 1, into the position required for threading the braid through the trimming or other article to which it is to 110 be applied.

If desired, the slots *c* and *d* may be omit-

ted and the braid passed directly through a slot *o* and over the projection *f* or *g*, as shown in Figs. 3 and 4. Thus the braid will be entirely concealed, if that arrangement should be preferred. It will also be understood that the braid need not be coiled in the form of a reel but may be arranged within the receptacle in any convenient way.

In Fig. 5, the invention is shown as applied to a flat card, the braid being wound about it in the usual manner. The card is provided with a projection *f* and ears *h* and *i* similar to the corresponding parts of Figs. 1 and 2, and the bodkin is secured to the card and attached to the end of the braid in the same manner as in the structure of Figs. 1 and 2.

In Fig. 6, the invention is shown as applied to a spool or reel, about which the braid is wound in the usual manner. The flat face of the reel is provided with a projection *f* and ears *h* and *i* similar to the corresponding parts of Figs. 1, 2 and 5, and the bodkin is secured to the card and attached to the end of the braid in the same manner as in the structure of Figs. 1, 2 and 5.

The invention is not limited to any particular form of holder, nor to the use therein or thereon of any particular kind of fabric, nor to the application of a bodkin of any particular shape so long as it is adapted to coöperate with a projection and securing devices as pointed out in the claims.

Having now fully described my invention, what I claim and desire to protect by Letters Patent is:

1. A combined holder for braid, etc. and

bodkin carrier comprising a holder adapted to contain a length of material, a braid-engaging projection on the holder adapted to engage an eye of a bodkin, and securing means arranged in front of the projection and adapted to engage the bodkin and co-operate with the projection to hold the bodkin in position.

2. A combined holder for braid, etc. and bodkin carrier comprising a holder adapted to contain a length of material, a braid-engaging projection on the holder adapted to engage an eye of a bodkin, and ears projecting from the holder in advance of the projection along lines spaced apart, said ears being located one in front of the other and each ear having a free end overlying the holder and extending toward the line along which the other ear projects.

3. A combined braid receptacle and bodkin carrier comprising a box adapted to contain a length of braid and having, along one side, slots through which the braid is alternately threaded in and out, a braid engaging projection on the outer face of the slotted side of the box and adapted to engage an eye of the bodkin, and bodkin-securing means arranged on the same face of the box in advance of the projection and adapted to engage the bodkin and co-operate with the projection to hold the bodkin in position.

In testimony of which invention, I have hereunto set my hand, at Atlantic City, N. J., on this tenth day of September, 1912.

EDWIN M. GOLDSMITH.
